UNITED STATES PATENT OFFICE.

ALFRED D. ANTOINE AND CLARENCE C. TRAVIS, OF CHICAGO, ILLINOIS; SAID ANTOINE
ASSIGNOR TO SAID TRAVIS.

CHECK-CONTROLLED VENDING-MACHINE.

1,196,067.

Specification of Letters Patent. Patented Aug. 29, 1916.

Application filed December 16, 1912. Serial No. 736,891.

To all whom it may concern:

Be it known that we, ALFRED D. ANTOINE and CLARENCE C. TRAVIS, citizens of the United States, residing at Chicago, in the county of Cook and State of Illinois, have invented certain new and useful Improvements in Check-Controlled Vending-Machines, of which the following is a specification.

10 This invention relates to improvements in check controlled vending machines and one of the objects of the invention is to provide an improved machine of this class having means for locking the mechanism against 15 operation after the last article has been delivered from the machine, thereby preventing a check or coin from being delivered into the machine and out of the reach of the operator when the machine is empty 20 of the articles to be vended.

A further object is to provide an improved check controlled mechanism having means whereby it will be impossible to operate the delivery mechanism unless a check 25 or coin of the proper denomination or character is employed.

A further object is to provide an improved form of casing for the articles to be vended.

30 A further object is to provide an improved machine of this class having a guard for protecting the articles so that the articles cannot be removed by the insertion of an instrument or wire into the machine.

35 A further object is to provide an improved machine of this class having an ejector for ejecting the articles, and means for locking the ejector against operation after the last article has been delivered 40 thereby, from the machine.

A further object is to provide an improved device of this class which will be simple, durable, cheap and compact in construction, and effective, efficient and positive in operation.

To the attainment of these ends and the accomplishment of other new and useful objects as will appear, the invention consists in the features of novelty in substantially 50 the construction, combination and arrangement of the several parts hereinafter more

fully described and claimed and shown in the accompanying drawings exemplifying the invention and in which:—

Figure 1 is a longitudinal sectional view 55 of an improved device of this class constructed in accordance with the principles of this invention and as taken on line 1—1, Fig. 7. Fig. 2 is a detail view partly in elevation and partly in section and as taken on line 2—2, Fig. 7. Fig. 3 is a sectional view taken on line 3—3, Fig. 1. Fig. 4 is a horizontal sectional view of a portion of the casing for the articles. Fig. 5 is a view similar to Fig. 2 with the parts shown in a 60 different position. Fig. 6 is a detail view in elevation of a portion of the side of the casing. Fig. 7 is a rear view of the parts shown in Fig. 1 with the back of the casing removed. Fig. 8 is a view taken on line 70 8—8, Fig. 9 with parts broken away and showing the parts in the positions which they will assume when a check of the proper denomination is deposited in the machine to operate the ejector. Fig. 9 is a sectional 75 view taken on line 9—9, Fig. 7. Fig. 10 is a detail longitudinal sectional view of a portion of the casing showing the ejector and the follower and the positions they will assume when the follower operates to lock the 80 ejector. Fig. 11 is a detail view, partly in section showing the locking stops of the elements of the check controlled mechanism.

Referring more particularly to the drawings and in the present exemplification of 85 this invention the reference numeral 15 designates generally a casing which is constructed of any desired size and configuration, the base of which casing is preferably somewhat larger than the upper portion of 90 the casing, and in which upper portion the articles 16 to be vended are located.

The casing is preferably constructed of sheet material and the upper part of the casing designated generally by the reference 95 numeral 17 comprises front and side walls, the latter being designated by the reference numeral 18. The extremities of these side walls 18 are deflected laterally as at 19 toward and terminate some distance short 100 of each other, so that the laterally deflected portions 19 together with the side walls 18

and the front of this portion of the casing constitute and form a chute for receiving and holding the articles 16. The chute thus formed is preferably of a size only slightly larger than the articles 16 and the deflected portions 19 terminate short of the upper extremity of the casing which latter is formed by the laterally deflected portion 20, (see Fig. 1), to form an opening through which the articles may be placed into the chute thus formed. The laterally deflected portions 19 also preferably terminate short of the enlarged portion 15 of the base of the casing, the casing being provided with an inclined portion 21 forming a closure for the space which would be formed between the base and the upper portion of the casing 17, as shown more clearly in Figs. 1 and 6. The casing being constructed of sheet material is provided with overlapping ends or edges as shown and these overlapping portions are secured together by any desired or suitable fastening device. Arranged adjacent the bottom of the chute and preferably beneath the extremities of the deflected portions 19 is a support 22 upon which the articles 16 rest, and a follower 23 rests upon the articles. The support 22 is preferably slightly inclined and is provided with an inclined wall 24, so as to properly position the articles on the support. A plate 25 is provided within the chute to form a partial closure for the opening between the reduced and enlarged portions of the casing and above the support 22. This plate 25 terminates short of the support 22 to form an opening 26 through which the articles are ejected, and a guard 27 is pivotally supported as at 28 so as to extend across the opening 26 to form a closure therefor to prevent the removal of the articles by the insertion of an instrument or wire through the opening 29 in the base 15 of the casing.

The support 22 is preferably formed as a part of a delivery tray 30 which is arranged within the casing and has a rear wall 31, while the forward extremity 32 projects through the opening 29 beyond the face of the casing. This support 22 and tray 30 are held in position in any suitable manner preferably by means of ears or lugs 33, 34 which are fastened to the sides of the casing. The back of the casing thus formed is open and a closure 35 is provided for this opening. This closure is provided with apertures or openings 36 through which suitable fastening devices 37 pass and by means of which closure the mechanism is supported. The closure is provided with a lip 38 at its lower extremities which hooks over a curved flanged portion 39 while the upper extremity of the closure is provided with a laterally deflected flange 40 which overhangs an upwardly projecting flange 41 on the top 20 of the casing. A fastening device 42 such as a lock is pro-

vided and which is operated by a key preferably along the front of the casing. The bolt of the lock passes through an aperture in a bracket or arm 43 carried by the closure 35 and which projects into the casing, so that when it is desired to gain access to the interior of the casing the fastening device is unlocked and the entire casing with the operating mechanism may be removed from the back or closure 35 by tilting the upper end forwardly and then unhooking the flange 39 from the flange 38. When the casing is thus removed the closure 35 will remain secured to the support to which it is fastened. The articles are then placed in the casing and the latter secured in position.

Arranged within the base 15 of the casing is the check controlled mechanism for controlling the discharge of the articles from the machine, and this mechanism will now be described. Arranged to rotate within a suitable casing 44 secured to the front of the casing and preferably below the tray 30 is a rotatable disk 45 which is provided with a pocket 46 opening through the edge of the disk, for the reception of the check and the casing 44 within which this disk rotates is also provided with an opening 45^a so that the check may be inserted into the pocket. A handle 47 is connected with the disk for rotating the same and one extremity of the handle 48 projects into the casing and is connected with a bearing element 49 journaled in a suitable support 50. Connected with the extension 48 of the handle so as to rotate therewith is an arm 51 which is provided with a shouldered extremity 52. This arm is provided with a laterally deflected portion 53 for a purpose to be hereinafter set forth and an elastic member 54 is connected by one extremity to the arm and is anchored by its other extremity to a fixed support. The elastic member is so arranged that it tends normally to move the arm 51 into the position shown in Figs. 7 and 8 and when the handle 47 is rotated to lower the notched extremity 52 of the arm, the elastic member 54 will be placed under tension. If desired the arm 51 may also be provided with a laterally deflected portion 55 to form a bearing for the elastic member when the arm is rotated. Pivotally supported by the bearing element 49 is another element 56 which operates with the arm 51, and this element 56 is provided with a laterally deflected portion 57 which extends under the arm 51 and forms a seat for the check 58. Spaced projections 59 are provided on the laterally deflected portions 57 against which the edge of the check engages and these projections 59 are spaced from each other a distance sufficient to accommodate a check or coin of a particular denomination or size so that when it is attempted to operate the mechanism with a smaller check and the check is depos-

ited on the seat 57 it will pass between the projections 59 and the element 56 will not be swung about its pivot.

The mechanism by which the check is delivered into the machine constitutes no part of the present invention but suffice it to say that when the check is deposited in the pocket 46 it will unlock the disk 45 to permit it to revolve a sufficient distance that the pocket 46 may become inverted and when thus inverted the check will drop out of the pocket and will pass down an incline 59^a, see Fig. 1, to be delivered to the seat 57. It will be obvious that in order to invert the pocket 46 the disk 45 must be rotated by the handle 47 and inasmuch as the arm is connected with the handle it will also be rotated. The arm 51 is so located with respect to the seat 57 that it will pass between the projections 59 previous to the time that the check is delivered to the seat. When the check is thus delivered to the seat the arm 51 will be in the rear thereof and the elastic member 54 will be placed under tension. If the check be a proper one, the notched extremity 52 of the arm, when the handle 47 is released to allow the elastic member 54 to operate upon the arm, will engage the edge of the check, and will force the check forwardly with respect to its seat 57 so that another portion of its edge will engage the projections 59. In this position, a further action of the elastic member on the arm will cause the arm through the medium of the check to become locked to the element 56 and this will cause the element to be swung about its pivot to raise the check seat into the position shown in Fig. 8 of the drawing, and the check will be held on its seat until the arm 51 moves away from the check which will permit the check to drop off of its seat and into the casing. Should a check which is not of the proper size be delivered into the machine and to the seat 57, it will be manifest that when the arm 51 is moved so that its notched extremity 52 engages the edge of the check, it will move the check on the seat 57 but inasmuch as it would not be of the proper size the arm will move it between the projections 59 and off of the check seat so that it will drop into the casing without swinging the element 56. The article to be vended is delivered from the machine and onto the tray 30 by a mechanism which operates directly in response to the actuation of the check control led mechanism thus described.

In the present exemplification of the invention the articles are delivered by an ejector designated generally by the reference numeral 60 and this ejector is pivotally mounted intermediate its ends as at 61 to move about a substantially horizontal pivot while the ejector swings in a substantially upright plane. The ejector is preferably

provided at one extremity with spaced fingers 62, the extremities of which are adapted to pass through openings 63 in the support 22 as shown more clearly in Figs. 7 and 10. The normal position of the ejector is such that the extremities of the fingers 62 will stand behind the article to be vended and when the ejector is swung about its pivot to move the fingers forwardly the lowermost article will be forced by these fingers through opening 26 and past the guard 27 to a position that it will drop from the support 22 and into the tray 30, from which latter it may be removed through the opening 29 in the base of the casing. After the article has been delivered the ejector is moved in the opposite direction about its pivot and from under the article so that another article will assume a position with its edge directly in front of the fingers to be ejected thereby at the next operation of the machine.

The mechanism whereby the ejector is swung about its point of pivotal support will now be described. The other end of the ejector 60 is shaped to form a cam 64 and the element 56 is provided with a laterally deflected portion 65 preferably provided with spaced anti-friction rollers 66 mounted thereon and between which anti-friction rollers a cam 64 of the ejector operates. The cam is so arranged that when the arm 51 is locked to the element 56 through the medium of the check, as heretofore described, the movement of the element about its pivot will cause the anti-friction rollers to operate upon the cam to swing the ejector 60 forwardly and thereby cause the fingers 62 of the ejector to eject one of the articles. After the article has been delivered and the element 56 is returned to its former position the anti-friction rollers will operate upon the cam to move the ejector in the opposite direction and into a position to eject the next article. After all of the articles have been delivered, the follower 23 will assume a position to rest upon the support 22. In order that this follower may be utilized as a locking means to prevent the insertion of a coin or check after the machine is empty which would cause the operator to lose the check, the follower is provided with recessed portions 67 in its forward edge and these recessed portions are so arranged that after the last article has been delivered and the follower drops upon the support within the path of the return movement of the fingers 62 of the ejector, the fingers will, upon such return movement enter these recesses and inasmuch as the fingers are notched on their rear faces 68 they will be held against return movement and inasmuch as the ejector cannot be returned to its normal position, the element 56 will through the medium of the cam 64 and the anti-friction rollers 66 be also held against return movement. In

order to provide means whereby the disk 45 cannot be rotated sufficiently to deposit a check from the pocket 46 onto the incline 59^a after the last article has been delivered 5 from the machine and the ejector 60 and element 56 are locked against return movement in the manner just described; the laterally deflected portion 53 on the arm 51 is provided and the element 56 is provided with 10 the face 69, see particularly Figs. 8 and 11, with which the laterally deflected portion 53 contacts. That is to say when the element 56 is held in the position shown in Fig. 8 by the locking of the ejector 60 by the following 15 23, and the arm 51 is rotated, its rotary movement will be arrested by the engagement of the laterally deflected portion 53 with the face 69 which latter is held within the path of movement of the portion 53. 20 This will occur before the pocket 46 in the disk 45 assumes a position to deposit the check upon the incline 59^a, thereby preventing the deposit of a check into the machine after the last article has been discharged 25 therefrom and also preventing the actuation of the check controlled mechanism. In order to hold in position the articles 16 which are superposed upon each other and to prevent them from passing over the edge of the 30 wall 24, the back 35 of the casing is provided with one or more forwardly inclined fingers 70 which extend from a point above the upper edge of the back 24 toward the said edge and terminate short thereof. 35 With this improved construction it will be manifest that it will be impossible for an operator to lose his check after the machine is empty, and by this construction of the casing, it will be apparent that the casing 40 itself forms the chute or hopper for the articles to be vended and obviates the necessity of providing an outer casing within which the chute is inserted, as is customary in all other machines of this type. Furthermore, 45 the casing being constructed out of sheet metal may be stamped and pressed into shape at a material reduction in the cost of manufacture.

50 While in the present exemplification of this invention the preferred forms of the parts and the preferred construction of the machine are herein shown and described, it is to be understood that many changes may be made in the details of construction and in the combination and arrangement of the several parts, within the scope of the claims without departing from the spirit of this invention. Obviously the anti-friction rollers 66 on the element 56 may be dispensed with and any other means provided which will operate on opposite sides of the cam 64 for the purpose designed.

55 With this improved construction it will be manifest that when the ejector 60 and the element 56 are in the position shown in Fig.

1 of the drawings, the ejector 60 will be locked against pivotal movement, the cam 64 being so shaped that it will effect this locking operation, and when thus locked it will be manifest that even should it be possible to insert an instrument within the casing so that it will engage the ejector, the ejector cannot be moved forwardly so as to eject one of the articles.

What is claimed as new is:—

1. A machine of the character described embodying an oscillating ejector for delivering the articles, said ejector having a comparatively wide extremity, a portion of said extremity being deflected laterally to form a cam surface, a pivotally mounted actuating element, the pivot of said element being disposed transversely of the pivot of the ejector, and means connected with the said element and movable over the said cam surface for swinging the said ejector.

2. A machine of the character described embodying an oscillating ejector for delivering the articles, said ejector having a comparatively wide extremity, a portion of said extremity being deflected laterally to form a cam surface, a pivotally mounted actuating element, the pivot of said element being disposed transversely of the pivot of the ejector, means connected with the said element and movable over the said cam surface for swinging the said ejector in one direction, and means for swinging the ejector in the opposite direction.

3. A machine of the character described embodying an oscillating ejector for delivering the articles, said ejector having a comparatively wide extremity, a portion of said extremity being deflected laterally to form a cam surface, a pivotally mounted actuating element, the pivot of said element being disposed transversely of the pivot of the ejector, and means connected with the said element and movable over opposite faces of the said cam surface for swinging the ejector first in one direction and then in the opposite direction.

4. A machine of the character described embodying an oscillating ejector for delivering the articles, said ejector having a comparatively wide extremity, portions of said extremity being deflected laterally in opposite directions to form a cam surface, a pivotally mounted actuating element, the pivot of the element being disposed transversely of the pivot of the ejector, and spaced means connected with the said element and between which means the said cam surface is confined.

5. A machine of the character described embodying an oscillating ejector, one extremity of the ejector being shaped to form an extended cam surface, an actuating element movable about a pivot disposed transversely of the pivot of the ejector, and means

- connected with the actuating element and movable over said cam surface for shifting the latter, a portion of the opposite extremity of the ejector being shaped to form a transversely disposed laterally projecting finger.
6. A machine of the character described embodying an oscillating ejector, one extremity of the ejector being shaped to form an extended cam surface, an actuating element movable about a pivot disposed transversely of the pivot of the ejector, and means connected with the actuating element and movable over said cam surface for shifting the latter, the edge of the opposite extremity of the ejector being bent laterally to form fingers, the extremity of the fingers projecting beyond the end of the body portion of said ejector.
- 5 15
6. A machine of the character described embodying an oscillating ejector, one extremity of the ejector being shaped to form an extended cam surface, an actuating element movable about a pivot disposed transversely of the pivot of the ejector, and means connected with the actuating element and movable over said cam surface for shifting the latter, the edge of the opposite extremity of the ejector being bent laterally to form fingers, the extremity of the fingers projecting beyond the end of the body portion of said ejector.
- 10 20
- In testimony whereof we have signed our names to this specification, in the presence of two subscribing witnesses, on this 12th day of December, A. D. 1912.
